WILLIAM BENTON ROBINSON, OF EASLEY, SOUTH CAROLINA.

PUMPING APPARATUS.

1,296,852.

Specification of Letters Patent. Patented Mar. 11, 1919.

Application filed January 22, 1917. Serial No. 143,744.

To all whom it may concern:

Be it known that I, WILLIAM BENTON ROBINSON, a citizen of the United States, residing at Easley, in the county of Pickens 5 and State of South Carolina, have invented certain new and useful Improvements in Pumping Apparatus, of which the following is a specification.

This invention has relation to well pumping apparatus, and has for an object to provide an apparatus intended to be placed in the bottom of a well, and embodying means operable to force the water upward to the level of the ground.

Another object of the invention is to provide a novel mechanism for automatically closing and opening a valve forming a part of my apparatus.

In addition to the foregoing my invention comprehends improvements in the details of construction and arrangement of parts to be hereinafter more fully described and particularly set forth in the appended claims.

In the accompanying drawings in which similar and corresponding parts are designated by the same characters of reference throughout the several views in which they appear:

Figure 1, is a view in vertical section of a well pumping apparatus constructed after the manner of my invention, illustrating the same as located in the bottom of a well.

Fig. 2, is a detail view in section illustrating the valve operating mechanism, taken on the line 2—2 of Fig. 1.

Fig. 3, is a view in plan of the valve operating mechanism, and

Fig. 4, is a detail view in plan of the valve.

With reference to the drawings 10 indicates a cylindrical casing disposed vertically and located in the bottom of a well, the casing being preferably supported in an outer casing 11 inclosing the lower portion 45 of the casing 10. The casing 10 is closed at its upper end as indicated at 12 and is provided in its side wall adjacent its upper end with an opening 13.

A cylindrical brass lining 14 is provided 50 on the inner side of the casing 10 adjacent the lower portion thereof, and a piston indicated generally at 15 is provided for movement within the casing and for engagement with the lining whereby a smooth surface is provided. The piston comprises a discous body portion 16 provided upon its upper

and lower sides and adjacent its periphery with flexible gaskets 17 which extend radially beyond the edge of the body portion of the piston for engaging the lining 14. 60 Annular rings 18 are applied to the gaskets and secured to the body portion of the piston for holding the gaskets in place.

The body portion of the piston is formed with an opening 19 adapted to be valve controlled, and to that end a disk 20 having an offset flange 21 is placed above said opening and secured by means of its flange to the edge of the opening through the medium of bolts 22. The disk 20 is provided with a plurality of radial openings 23 and a central opening 24 through which the lower end of a vertically extending valve rod 25 projects. A valve is provided in the form of a disk 26 which is applied to the under side of the disk 20 and is formed with radial openings 27 corresponding in shape and size to the openings 23. A plate 28 is applied to the under side of the valve 26 and is secured by means of a peripheral flange to the under side of the disk 20 whereby the plate is supported for rotation between the plates 20 and 28. The lower plate 28 is similarly provided with radial openings 29 and a central opening through which the valve stem projects a nut being preferably provided to said projecting end of the valve rod. 85

The valve rod 25 is supported at a point intermediate its length in a bearing 30 having a laterally projecting arm 31 formed with a longitudinally extending slot 32. A standard 33 is extended horizontally from one side wall of the casing 10 and is adapted to be connected to the arm 31 by means of a bolt 34 provided on the standard and which extends through the slot 32 of the arm. It will be obvious that the bearing 30 will be adjustable toward or away from the casing to permit the bearing to be centered so that the valve rod 25 may slide freely therein during movement of the piston. The arm 31 is formed with oppositely extending arms which extend at an angle to the valve rod and are provided on their extremities with rollers 35. The upper arm is indicated at 36 and the lower at 37. An arm 38 is adjustably connected to the upper end of the valve rod through the medium of a collar 39 formed on said arm and through which collar the valve rod projects, a set screw 40 provided on the collar serving to retain the arm in adjusted position. The outer extrem- 100 105 110

ity of the arm 38 is provided with a cam member 41 which is inclined at an angle with respect to the valve rod and in the vertical plane coincident with the roller 35 of the above mentioned arm 36. A second arm 42 is adjustably connected to the valve rod at a point below the arm 38 and is provided with a cam member 43 disposed at an angle relative to the valve rod and at right angles 10 to the direction of inclination of the cam member 51, the arm 42 being disposed diametrically opposite the arm 38. The cam member 43 is located also in a vertical plane coincident with the plane of the roller 35 of the arm 37.

A piston rod 44 is connected at its lower end to the piston 15 centrally thereof with its upper end projecting through a central opening in the cover 12, a collar 45 adjustably secured to the piston rod abutting against the under side of the cover to limit upward movement of the piston. A post 46 is erected upon the cap 12 exteriorly of the casing 10 to support at its upper end a pulley 47 around which a flexible element 48 passes, with one end of said element connected to the piston rod as at 49, and the opposite end provided with an adjustable weight 50 to counterbalance the weight of 30 the piston and appurtenant parts.

A stand pipe 51 is located in the well with one end in communication with the casing 10 at the bottom thereof, and the opposite end located at the surface of the ground. A check valve 52 is interposed in the stand pipe adjacent its lower end to prevent flow of water in the pipe in a downward direction, a manually operable valve 53 being provided in the stand pipe adjacent its upper end. The piston rod 44 is formed with an extension 50 which extends upward and is connected to an operating lever 61 fulcrumed upon any convenient stationary support whereby the piston rod and piston may be reciprocated.

In operation, and assuming the parts to be in the position shown in Fig. 1, the water will flow from the well through the opening 13 into the upper portion of the casing 10 and will accumulate above the piston. It will be remembered that the disk valve 26 is in such a position as to dispose its radial openings 27 out of alignment with the openings in the disks disposed above and below. Downward pressure is now applied to the piston rod 44 by any suitable means such as that illustrated in the drawings whereby to force the water beneath the piston and up through the stand pipe. 50 When the piston has reached its lowermost position the weight 50 will have been drawn upward and the lower end of the cam member 41 brought into engagement with the roller 35 of the arm 36. However, before the 60 piston has reached its extreme lowermost po-

sition, the cam member will ride over the pulley thereby partially rotating the valve rod to rotate the disk valve 26 to dispose its openings in registration with the openings in the disks located thereabove and below. 70

The interior of the casing 10 above and below the piston having thus been placed in communication the piston is now moving upward, the water being displaced from one side of the piston to the other until the 75 lower cam member 43 engages the roller 35 of the lower arm 37 whereupon partial rotation of the valve rod will take place to rotate the disk valve 26 thereby moving the same to closed position. When the upper 80 portion of the casing 10 is again filled a repetition of the foregoing operation will take place.

While I have illustrated and described my invention with some degree of particularity, I realize that in practice various alterations thereover may be made, and I therefore desire to reserve the right and privilege of changing the form of the details of construction, or otherwise altering 90 the arrangement of the correlated parts without departing from the spirit of the invention or the scope of the appended claims.

Having thus described my invention, 95 what I claim as new and desire to secure by Letters Patent is:—

1. A well pumping apparatus including a cylinder to be disposed vertically in a well, a stand pipe extending from the surface of the ground into the well and having its lower end in communication with the lower end of the cylinder, a check valve in the lower end of the stand pipe, a piston movable vertically in the cylinder and having an opening, a rotary valve for controlling said opening, cam means for opening the valve when the piston has reached its lower position, similar means for closing the valve when the piston has reached its upper position, means for reciprocating the piston, and gravity means for counterbalancing the weight of the piston.

2. A well pumping apparatus including a cylindrical container to be disposed vertically in a well, a stand pipe extending from the surface of the ground into the well and having its lower end in communication with the lower end of the casing, a check valve in the lower end of the standpipe to prevent downward flow of water therein, a piston movable vertically in the casing and having an opening, a valve for controlling said opening comprising spaced plates secured over said opening, said plates having aligned apertures, a disk valve mounted for rotation between the plates and having openings whereby the valve may be in open position when the openings of the valve and plates are in alignment, a valve rod for ro- 130

tating said valves, means operable when the piston has moved to a lowermost position to rotate the rod to open the valve, gravity operable means for counterbalancing the weight of the piston, means operable when the piston has reached its upper position to rotate the rod and return the valve to closed position, and means for reciprocating the piston.

10 3. A well pumping apparatus including a cylindrical casing adapted to be disposed vertically in a well, a stand pipe extending from the surface of the ground into the well and having its lower end in communication 15 with the lower end of the casing, a check valve in the lower end of the stand pipe to prevent downward flow of water therein, a piston movable vertically in the casing and having an opening, a rotatably mounted 20 valve for controlling said opening, a vertically extending rod connected to said valve

for operating the same, oppositely extending arms on said rod in vertical spaced relation having cam members operable to rotate the rod in opposite directions, means 25 for supporting rollers in the path of movement of said members, one cam member may engage a roller when the piston has reached its lowermost position to rotate the rod and thereby open the valve, means for returning 30 the piston to raised position whereby the other cam member may engage a roller to rotate the rod and then return the valve to closed position, and means for reciprocating 35 the piston.

In testimony whereof I affix my signature in presence of two witnesses.

WILLIAM BENTON ROBINSON.
